United States Patent Office

Des. 186,740
Patented Nov. 24, 1959

186,740

TYPEWRITING MACHINE

Raymond Spilman, Darien, Conn., and Charles A. Jerabek, Bayshore, and Roger Engel, Forest Hills, N.Y., assignors to Underwood Corporation, New York, N.Y., a corporation of Delaware

Application December 11, 1958, Serial No. 53,732

Term of patent 14 years

(Cl. D64—11)

FIG. 1

The dominant features of our design reside in the portions of the machine shown in solid lines.

We claim:

The ornamental design for a typewriting machine, as shown and described.
